UNITED STATES PATENT OFFICE

WILLIAM B. HAY, OF PORTLAND, MAINE

BLADE HOLDER

Application filed August 10, 1931. Serial No. 556,279.

This invention relates to a hand tool or device for holding razor blades to enable efficient stropping thereof. It has as an essential object the provision of a blade holder 5 which is adaptable for maintaining in gripped relation either double edged blades or blades of the single edge type.

Another object of the invention is the provision of a blade holder which is simple and 10 rugged in construction, being formed of pressed metal parts and which can be made up at an exceedingly low manufacturing cost.

Other objects of the invention provided with 15 guide means for insuring proper disposition of the device in relation to a strop with which the same is employed; the provision of a blade holder having means detachably associated therewith for rendering the holder 20 adaptable to different types of razor blades; the provision of an improved blade holder having a hinged portion cooperable with the body thereof for clamping a razor blade therebetween; and the provision of novel 25 structural details in blade holders of this general type.

The embodiments disclosed herein constitute the preferred structural arrangements by which the invention is reduced to practice 30 at the present time. It is intended that the details shown and described shall not constitute limitations inconsistent with the scope of the invention as claimed.

This application is a continuation as to all 35 common subject matter of my prior applications Serial Number 530,985 filed April 17, 1931 and Serial Number 540,471 filed May 27, 1931.

In the drawings:

40 Figure 1 is a side elevation of a holder constructed in accordance with the invention.

Figure 2 is a top plan view thereof.

Figure 3 is a plan, partly in section of the lower section of the holder.

45 Figure 4 is a longitudinal section through the holder.

Figure 5 is a section on line 5—5 of Figure 3.

50 Figure 6 is a perspective of a spline member for anchoring blades in the holder.

Figure 7 is a top plan view of an alternative embodiment of holder.

Figure 8 is a side elevation thereof.

Figure 9 is a perspective of the top section 55 shown in Figures 7 and 8.

Figures 10 to 14 inclusive are detail illustrations of a securing means for retaining the sections in closed position.

Figure 15 is a sectional detail of an alternative retaining means for holding the sections closed. 60

In the form as shown in Figures 1 to 6 inclusive the blade holder comprises a body of stamped or pressed sheet metal arranged as an elongated strip body portion comprising 65 a bottom section 16 shaped as a shallow V to provide oppositely inclined side faces 17 and 18 having flat edge flanges 19 and 20 respectively. Substantially one-half of the holder comprises a handle portion formed by overlapping on the base portion 16 a complementary handle portion 21 having a flat edge flange 22 which is adapted to be welded or otherwise suitably secured to the edge flange 70 20 of the bottom section, cooperating therewith to provide the handle for the holder. This upper portion 21 of the handle is integral with the bottom section being folded over from one side edge as shown in Figures 75 3 and 7.

At its outer extremity the other half of the bottom portion 16 terminates in an upstanding perpendicular lip 23 which is centrally slotted as at 24 to receive therethrough the tongue 25 of a top or upper clamping section 26 which is of a length sufficient to overlie that portion of the base 16 which is not taken up by the handle portion. The tongue 25 is carried at the outer end of the top section 26 and adjacent its inner end this top section, which is complementary in configuration to the bottom section 16, is provided at its side edges with lateral spring clips 27 which are adapted to snap down over the side edge flanges 19 and 20 of the base portion to hold the top section 26 clamped in secured position against the base portion. When the clips 27 are released the top section 26 may be swung upwardly on the hinge formed at its outer end by the engagement of the tongue 25 80 85 90 95 100

through the slot 24 of the base section lip 23. At suitably spaced intervals the respective edge flanges 19 and 20 of the base portion are crimped to provide upstanding lugs 28 which 5 are adapted to be engaged within recesses formed by upwardly crimped portions 29 in the edge flanges of the top section 26. These crimped portions serve as guides for proper 10 positioning of the top and bottom sections 15 when they are assembled in clamped relation with a blade engaged therebetween, and the lugs 28 serve to keep single edge blades from sliding out of position longitudinally.

As in a stropping operation it is important 15 to restrain the holder and strop against relative sidewise slipping the lower and upper sections are respectively provided with spaced pairs of aligned upstruck guide lugs 30 and 31 extending from the apexes thereof.

20 At its apex the lower or base section 16 is provided with longitudinally spaced inwardly struck parallel lugs 32 having terminal lips 33 directed toward each other in a common horizontal plane slightly beneath 25 the plane of the side flanges 19 and 20. These anchoring lugs 32 are adapted to be sprung apart slightly to engage a flat spline plate 34 at its ends beneath the terminal lips 33, which plate functions to hold double edge 30 blades within the holder.

At longitudinally spaced intervals the spline plate is provided with perpendicular up-struck lugs 35 which are sufficiently spaced for proper registry in the usual central apertures 36 which are characteristic of double edged blades known to the art at the present time. One of these blades indicated 35 by the reference numeral 37 is shown in applied position in Figure 3 wherein the shank 40 of the blade is disposed with its apertures 36 engaged over the holding lugs 35 of the spline plate with its edge portions 38 projecting beyond and overlying the edge flanges 19 and 20 of the bottom section.

45 The disposition of the lugs 32 holds the spline plate 34 against endwise movement and the engagement of the holding lugs 35 on the spline plate will retain the blade against shifting movement within the holder. The ends of spline plate 34 are formed with notches 34' which receive the shanks of the lugs 32 to retain the plate against lateral shifting within the holder.

In assembling the holder the top section 26 50 may be either swung up by reason of its hinged connection with the bottom portion or may be removed entirely therefrom as illustrated in Figure 9. The spline plate 34 is then brought into its proper engaged position in the bottom section and the blade 37 placed over the holding lugs 35. The top section 26 is then replaced with its tongue 25 passed through the slot 24 in the base section end 55 lip and the clips 27 are snapped into engagement over the edge flanges 19 and 20 of the

base whereby the blade 37 will be firmly secured in position and the holder may be employed in connection with a stropping element, the oppositely inclined side faces of the respective top and bottom sections providing a proper angled engagement of the holder with the stropping element so that in manipulation thereover it is not necessary to lift the holder from its engagement with the strop.

70 A positive locking means comprising a key 39 is provided for retaining the sections of the holder closed over a blade. This may be used either with or without the spring clip 27. The key 39 is a flat thin blank which, as shown in Figure 5, has an enlarged head 40, a central enlarged portion 41 of lesser size and an enlarged tip 42 of smaller size than the central portion 41. In one position the key is adapted to be inserted through registering key slots 43 and 44 in the respective holder sections 16 and 26 after which it is given a quarter turn to engage the head 40 and tip 42 over the respective sections thus locking the sections in closed position.

75 In the embodiment illustrated in Figures 7 to 14 inclusive like reference characters indicate parts identical with parts previously described. In this form the edge flanges 19 and 20 of the bottom section 16 are formed with integral laterally projecting flat guide lugs or ears 45 arranged as longitudinally spaced pairs. Similar ears 46 are formed on the edge flanges of the top section 26 and are adapted to overlie the ears 45. These guide ears are arranged with slightly diverging opposed edge faces, as best shown in Figure 7, positioned adjacent the respective guide lugs 30 and 31 with which they cooperate in turning the holder upon a strop when a single edge blade is retained in the holder.

80 In Figures 7 to 14 inclusive there is also illustrated an alternative embodiment of the means for securing the sections in closed position. This means consists of a T slot 47 in the handle portion 21 adapted to receive and retain in the leg portion thereof the shank 48 of a locking finger extending from the inner end of the top section 26 and formed with a downturned head 49 which is adapted to pass through the head of the slot 47 and be retained under the apex of the handle.

85 In effecting this locking engagement the top section 26 is slid longitudinally over the bottom section, the engagement of the tongue 25 at the outer end through the slot 24 permitting the necessary play in the parts.

90 In Figure 15 is shown a locking means which may be employed in lieu of the key and slot shown in Figures 1 to 5. This means consists of a locking bolt having a shank 50 adapted to be passed through an aperture 51 at the apex of the top section 26 and to be threaded at its lower end into engagement

with the bottom section 16. An operating head 52 is provided on the bolt for engagement over the apex of the top section.

I claim:—

- 5 1. In a razor blade holder, complementary sections adapted to be connected to clamp a razor blade therebetween, lateral edge flanges on said sections, and strop guide lugs integral with said edge flanges and extending laterally therefrom in the planes of the flanges in pairs spaced apart a distance greater than the length of a razor blade, said lugs having their opposed edges oppositely and outwardly inclined.
- 10 15 2. A razor blade holder comprising a substantially trough shaped base section, a top section detachably mounted on said base and complementary thereto, means for securing said sections together to clamp a razor blade therebetween, said sections having flat side edge flanges to provide a support for a blade with the blade extending laterally beyond the flanges, said sections at the top and bottom having upstruck lugs beyond each end of a
- 20 25 30 razor blade engaged in the holder whereby to provide strop guides, and guide lugs extending from the side edge flanges in the planes of the flanges, all of said guide lugs being disposed substantially in common planes transversely of the holder beyond each end of a blade carried in the holder.

In testimony whereof I affix my signature.
WILLIAM B. HAY.
